UNITED STATES PATENT OFFICE.

PHILIP BRUNELLE, OF BELFIELD, NORTH DAKOTA, ASSIGNOR OF ONE-HALF TO
H. E. HANEY, OF BELFIELD, NORTH DAKOTA.

DETACHABLE PLOW-POINT.

1,281,283.

Specification of Letters Patent. Patented Oct. 15, 1918.

Application filed May 18, 1918. Serial No. 235,286.

To all whom it may concern:

Be it known that I, PHILIP BRUNELLE, a citizen of the United States, residing at Belfield, in the county of Stark, State of North Dakota, have invented a new and useful Detachable Plow-Point; and I do hereby declare the following to be a full, clear, and exact description of the invention, such as will enable others skilled in the art to which it 10 appertains to make and use the same.

This invention relates to an improved detachable point for a plow share, and one of the objects of the invention is to provide a device of this kind, which is simple, efficient 15 and practical in construction, and may be manufactured at a small cost and sold at a reasonable profit.

A further object of the invention is to provide a device of this kind comprising improved features of construction, one of 20 which consists in the provision of a pocket formed in the detachable point, for the reception of the end of a plow share, in combination with a lug carried integrally by one 25 wall of the pocket and engaging adjacent the share landside of the plow share and being secured thereto, thereby holding the pocketed point to the share.

In practical fields the details of construction may necessitate alterations falling within the scope of what is claimed.

The invention comprises further features and combination of parts as hereinafter set forth shown in the drawings and claimed.

35 In the drawings:—

Figure 1 is a view in perspective of the improved detachable share point as applied to a share.

Fig. 2 is a perspective view of a portion 40 of the share showing its opposite sides, and the point applied.

Fig. 3 is an enlarged detail perspective view of the point detached.

Fig. 4 is a sectional view on line 4—4 of 45 Fig. 2.

Fig. 5 is an enlarged detail perspective view of a portion of the share, and the point applied.

Referring more especially to the drawings, 50 1 designates a portion of a share and 2 denotes a share landside. The share and the share landside flange 2 are at acute angles, and adjacent where the share merges into a curved forward edge 3, said share is V- 55 shaped in cross section. A short distance

from the forward curved edge 3, the share landside flange 2 terminates into a shoulder 4. The point 5 is provided with a forward cutting edge 6, and cutting edge 7. This detachable point 5 is constructed from a single piece of metal, bent upon itself, and where the bend is made, the folded parts are welded together and drawn to the shape shown clearly in Figs. 1, 2 and 5, and constructed with said cutting edges 6 and 7. 60 One side of the point overlaps the outer face of the share 1 which has an upper cutting edge 8, which merges into the upper cutting edge 7, as shown clearly in Fig. 1. Between the two sides 9 and 10 of the detachable plow 70 point a pocket 11 is formed, for the reception of the end part 3 of the share. The side 10 of the detachable point has an integral extension lug 12 provided with a slot 13 for the reception of the bolt 14, which 75 passes through the share, there being a nut 15 threaded on the bolt for drawing the washer 16 tight against the extension lug 12. The side 10 of the point has a shoulder 17 to engage the shoulder 4 of the landside 2. 80 The extension lug 12 has its under edge overlying the landside as shown clearly in Fig. 2. By means of the disposition of the extension lug 12, the inter-engaging shoulders 4 and 17, and the engaging curves of the pocket 85 and the end 3, the detachable point is held against displacement during its passage through the soil. By removing the bolt 14 the point may be detached and sharpened 90 and replaced, or a new point substituted. 90

The invention having been set forth what is claimed as new and useful is:—

1. The combination with a share having a forward curved end portion, of a point constructed from a single piece of metal bent on itself and welded and drawn to a point and provided with a pocket between the folded parts, the inner end of said pocket being curved and engaged by the forward curved portion of the share, one side of the pocket having an extension lug engaging the rear face of the share and overlying the share landside, one side of the pocket and the share landside having inter-engaging shoulders and means passing through the extension lug and the share for clamping the parts together. 95

2. The combination with a share having a forward end portion curved longitudinally and tapered, of a point constructed from a 100

105

110

single piece of metal bent upon itself subsequently welded and drawn to a point having a cutting edge and provided between the folded parts with a pocket curved longitudinally and tapered correspondingly to and receiving the forward longitudinally curved end portion of the share, the share landside having a shoulder, one of the folded parts of the point having a shoulder abutting the shoulder of the share landside, and also provided with an extension lug engaging the rear face of the share and overlying the share landside, said lug having an elongated slot, and means passing through the share

and through the slot and provided with a 15 securing device for clamping the parts together, said share landside extending at a slight acute angle to the rear face of the share and coöperating with the lug, whereby excessive tension is relieved on the securing 20 device.

In testimony whereof I have signed my name to this specification in the presence of two subscribing witnesses.

PHILIP BRUNELLE.
